METAL SCREEN

Bill E. Butler and Emmett A. Shaw,
Shreveport, La.

Application April 1, 1946, Serial No. 658,644

4 Claims. (Cl. 160—394)

1

Our invention relates to sash, door, and screen constructions, but more particularly to features of construction in metal screens.

An object of our invention is to provide a window screen that comprises both a screen surface and a burglar proof protecting grill.

Another object of our invention is to provide a clamping type frame designed to hold frictionally a layer of screen wire and a protecting guard member in assembled positions, a clamping member which does not require the use of any screws, bolts, or the like in the assembly of the same.

Another object of our invention is to provide means for mounting a metal screen or other type of screen in a window frame, the means including a pair of stationary studs extending out of one side edge of the screen in the plane of the screen adapted to fit into socket holes formed in one side of a window frame, and provided with a pair of spring pressed plungers terminating in studs that are adapted to fit in a second pair of sockets formed in the opposite side wall of the window frame.

Our invention in screens, generally speaking, inheres in novel framing elements for use in assembling a layer of screen wire and protecting mesh together. The framing elements are made out of a springy sheet metal material cut into strips two or three inches wide and then bent into wedge shaped channel members with the channel walls inclined inwardly toward each other. When the channel walls are forced over the edges of the protecting grill, with portions of the screen lapped over the same, the walls of the channel in the assembled clamping position are left resiliently spread. These springy wedge shaped channel frame members grip the edges of the assembled layer of screen and the protecting grill over which edge portions of the screen layer are folded. The channel members maintain their grip on the screen and edge of grill sandwiched in between layers of the screen throughout the entire life of the metal screen.

No screws or bolts are needed in our type of metal screen construction. When the end and side members of the channel frame are driven into place they are soldered together along their joining lines.

In the drawings,

Figure 1 is a plan view of a metal screen made according to the teachings of our invention shown in its assembled position in a window frame.

Figure 2 is an enlarged plan view of a retaining

2

means incorporated in the metal screen illustrated in Figure 1.

Figure 3 is an enlarged cross-sectional view of a frame construction feature of the screen illustrated in Figure 1 taken on line 3—3 of Figure 1, and,

Figure 4 is an enlarged plan view of a key used to operate a retaining means incorporated in the screen illustrated in Figure 1.

10 Referring to the drawing numeral 10 designates a grill which is preferably made out of a high carbon steel, hard enough to resist even a hacksaw blade. The grill 10 is made up of diagonally extended rods 11 which are welded to a 15 rectangular rod frame 12 which includes top and bottom end members 13, a right-hand side member 14 and a left-hand side member 15. The left-hand side member 15 is made up of three pieces, a central portion 16, an upper end extension 17 and a lower end extension 18.

A layer of screen mesh 19 of greater area than the grill 10 is laid on the grill 10 in the assembly of the screen. Portions of the screen 19, shown folded over the end members 13 of the rod frame 25 12 and marginal portion of the diagonally extending rods 11 as best seen in Figure 3, are designated by numeral 20. The portions of the screen mesh 19 folded over the right-hand side member 14 and the left-hand side member 15 are designated by numeral 21. When the screen mesh 19 is assembled on the grill 10, in the manner above described, the members of the clamping frame 22 are pressed on, which clamping frame is made up 25 of a pair of separate channel shaped end members 23 including a base portion 24 from which extends inwardly inclined side walls 25 and side channel members 26 including base members 27 and side walls 28.

When assembled, the side member 26 and end member 23 are soldered together along the solder lines 29. The soldering is done principally to improve the looks of the frame. The members of the frame, side members 26 and end members 23, individually maintain their grip on the edge portion of the assembled screen mesh 19 and the grill 10. Each member of the frame is made out of a strip of springy sheet metal material.

During the assembly of the end members 23 and the side members 26, as illustrated by Figure 50 50 3, the base member 24 of the end member 23 is forced down into pressing contact with the portion of the screen mesh 19 that is folded around the end member 13 of the rod frame 12. To start the end member 23 on the assembled screen mesh 55 19 and grill 10 the side walls 25 at one end must

be sprung apart from the normal nearly closed position, as indicated by the dotted lines in Figure 3, to a width equal to the combined thickness of the two layers of screen mesh 19 and the end member 13 enclosed by the screen mesh 19. In the assembled position of the end members 23 and side members 26 of the clamping frame 22, the base 24 and side walls 25 of the end members 23 and the base members 27 and side walls 28 of the side members 26 are all maintained in pressing contact with the screen mesh 19 due to the resiliency of the clamping frame 22.

The means and method of mounting the above described metal screen, or for that matter a wooden screen, or other prior art type of screen, we will now explain.

On the right-hand side member 14 of the rod frame 12 a pair of studs 30 are welded. The studs 30 extend through holes made in the base members 27 of the side members 26. The studs 30 extend in the plane of the screen and at a right angle to the right-hand side member 26 of the clamping frame 22. The studs 30 are adapted to fit into sockets S formed in the window frame W, which sockets S are preferably lined with tubular metal socket liners L. The same type of sockets S and socket liners L are employed on the left-hand side of the window frame W to receive the locking studs 36 of the plungers 35 of the locks 31 which we will now describe in detail.

As a means of holding the metal screen in the window frame W we employ a pair of duplicate locks 31, both of which are located on the left-hand side of the screen as seen in Figure 1, only one of which we will describe. The lock 31 includes a shell 32 which is welded into the left-hand side member 15 in the manner previously explained. At the outer end of the shell 32 a washer 33 which defines the keyhole and serves as a guide for a key is entrapped in the shell to serve as a spring retainer. At its inward end the shell 32 is provided with an inwardly extending plunger stop flange 34. Both ends of the shell 32 are crimped with a tool after the plunger 35, the compression spring 39, and washer 33 have been installed in the shell 32 to form the stop 34 and to entrap the washer 33. The plunger 35 includes a locking stud 36 which moves through a hole not shown in the left-hand base member 27 of the side member 26 of the clamping frame 22. The compression spring 39, interposed between the internally threaded boss 37 forming an integral part of the plunger 35 and the washer 33, urges the plunger 35 into locking position, a position in which the stud 36 has been moved into the socket S.

To remove the locking stud 36 the plunger 35, of which it forms an integral part, must be pulled out against the pressure of the compression spring 39. This is done by means of a threaded rod key 40 provided with a threaded end portion 41 adapted to engage the internally threaded boss 37. The rod is terminated at its other end in a

loop 42 adapted to be gripped by the fingers of the operator.

During the placing of the screen in the window frame W and the removal of the same both of the plungers 35 of the two locks 31 are withdrawn by a pair of keys 40. We have purposely hidden the shells 32 of the locks 31 in between the side walls 28 of the side members 26. The outer end of the shell 32 is positioned inwardly of the edges of the side walls 28 so that even the key-hole, the opening defined by the washer 33 is hidden from view.

The screen frame proper may be made of any springy metal sheet material. A galvanized steel material or a bronze or a copper material are preferred since such materials resist rust.

Having thus described our invention we claim:

1. A metal screen, comprising a guard member, a screen layer laid on the guard member, the screen layer clamped to the guard member along its peripheral area, by a channel shaped spring type clamping frame member mounted in an embracing position about the guard member and the screen layer along an edge portion of the guard member.

2. A metal screen, comprising a guard member, a screen layer laid on the guard member, a portion of which is lapped around an edge portion of the guard member, the folded portions of the screen layer enclosing the edge portion of the guard member embraced by a channel shaped spring type clamping frame member mounted in an embracing position about the two layers of the screen member and the guard member between the layers of the screen member.

3. The device as claimed in claim 2, wherein the clamping frame member consists of a flat base portion from which arises two inwardly inclined side walls.

4. The device as claimed in claim 2, wherein the clamping frame member consists of a flat base portion from which arises two inwardly inclined side walls, and wherein the frame member is mounted on the screen layers and the edge portion of the guard member between the screen layers in a position to bring the base portion of the guard member into pressing contact with the portion of the screen layer surrounding the edge portion of the guard member, whereby the base portion of the clamping frame will assist in clamping the screen layer to the guard member.
